ARTIFICIAL CHRISTMAS TREE

Theodore D. Boganowski, 3059 S. 48th Ave., Omaha,
Nebr. 68106, and Theodore L. Boganowski, 3003
Kansas Drive, Bellevue, Nebr. 68005

Filed Apr. 6, 1973, Ser. No. 348,726

Term of patent 14 years

Int. Cl. D11—02

U.S. Cl. D29—1 A

FIG. 1.

FIG. 1 is a side elevational view of an artificial Christmas tree showing our new design;

FIG. 2 is a fragmentary perspective view of one limb, all limbs being alike; and

FIG. 3 is a bottom plan view.

We claim:

The ornamental design for an artificial Christmas tree, as shown and described.
